ELECTRON DISCHARGE DEVICE HAVING A
CAVITY RESONATOR PROVIDED WITH A
TUNING ELECTRODEWilliam E. Shoupp, Wilkinsburg, Pa., assignor to
Westinghouse Electric Corporation, East Pitts-
burgh, Pa., a corporation of Pennsylvania

Application September 27, 1944, Serial No. 555,943

14 Claims. (Cl. 315—40)

1

This invention relates to electron discharge devices generally referred to as magnetrons, and more particularly to tuning means for the same.

A recent development in this art has been termed "crown of thorns" as somewhat descriptive of a tuning means for a magnetron, and consisting of a plurality of prongs, one in each of several resonant cavities of a magnetron, and carried from a complete or partial ring at the ends of the cavities so the several prongs may be moved longitudinally and simultaneously in the cavities. The ring is mechanically connected by rod or lever through a flexible part, such as a bellows or diaphragm so as to obtain mechanical control of movement and position of the "crown of thorns" within the magnetron. Aside from the mechanical difficulties of sealing, lateral displacement and the like, that structure also has the disadvantage, for enabling the ring to be moved, of requiring a larger end space in the magnetron with resultant greater spacing apart of the pole pieces of the magnet than in the usual magnetron where no "crown of thorns" is employed.

Broadly stated, then, an object of the present invention is to provide a tuning means and/or a frequency modulation means for a magnetron which will accomplish tuning by electrical methods, thereby avoiding the adverse structural and operational characteristics related above for the "crown of thorns" method.

Likewise of general nature, the invention contemplates operator control of internal tuning means but without transitional movement of mechanism from exterior to interior of the magnetron.

More in detail, the invention has for an object to provide a capacitative tuning means within a magnetron while maintaining the prior art dimensional characteristics of the magnetron.

Another object of the invention is to electrically control the functioning of the tuning means from the exterior of the magnetron.

Yet another object of the invention is to apply capacitative tuning means most effectively in the magnetron.

Other objects of the invention will appear to those skilled in the art as the description progresses, both by direct recitation thereof and by inference from the context.

Referring to the accompanying drawings in which like numerals of reference indicate similar parts throughout the several views:

Figure 1 is an axially longitudinal section of a magnetron showing my improved tuning means therein;

Figure 2 is a plan of the construction of Fig. 1, but with the cover or end plate removed; and

Figure 3 is a detail sectional view of a part of the magnetron as on line III—III of Fig. 2, showing ring supporting means.

2

In its general aspects, the invention provides fixed means within the end spaces of the magnetron, here shown as rings, between which extend a plurality of tuning elements. Each tuning element passes longitudinally through a constricted part of one of the resonant cavities of the magnetron, and is shown eccentric to the cylindrical part of such cavity here depicted as using that conventional shape. The invention, however, is not limited to this shape of cavity and location of tuning element. Furthermore, while the present showing shows one of the tuning elements in each resonant cavity, it is within the scope of the invention to utilize the tuning elements in any number of the resonant cavities desired and for range of tuning which the number employed will accomplish.

Referring now specifically to the embodiment of the invention illustrated in the several figures, 20 the reference numeral 10 designates a cylindrical metallic magnetron body, the ends whereof have cover or end plates 11 sealed thereon that the interior may be evacuated. Within and as an integral part of said body is the usual magnetron anode structure 12 of generally cylindrical shape but shorter than the outer part of the body so as to provide end spaces 13 between the anode and said end plates 11. The anode structure is axially hollow to provide a cathode cavity 25 and radiating from this cathode cavity are a plurality of resonant cavities 14, each having in the form shown a cylindrical portion parallel to the cathode cavity and each cylindrical portion having a longitudinal constricted capacitative slot 30 15 constituting a lateral opening from the cylindrical portion of the cavity into the hollow central part of cathode chamber of the magnetron. Said slots 15 extend the full length of the anode body so as to be open at their ends into said 35 end spaces 13. The ends of the cathode cavity and the ends of said resonant cavities likewise 40 open into the end spaces 13.

A cathode 16 passes axially through the cathode cavity, adequately spaced from the anode and supported as usual from lead-in rods 17 entering the end cavities at the sides thereof. An output loop 18 is situated in one end space, likewise passing out through the side wall of the end space. The size and shape of the magnetron body, the end spaces, anode, cathode and leads above described are preferably all in accordance with prior art practice, in consequence of which the pole pieces of the magnet (not shown) will have the same relation to the magnetron and its anode as exists in magnetrons as heretofore used.

In carrying out the present invention, a ring 19 is shown concentrically situated in each end space 13, said ring being conductive and spaced from the anode, end plates, and body wall of the 60 end space. Said ring has a diameter substan-

tially locating the ring in proximity to the collar-like part of the magnetron body portion so as not to be opposite the several resonant cavities any more than necessary and thus removed from interception of the magnetic lines of force from the ends of the cavities.

A lead-in rod 20 entering at one side of the end space, free of contact with the end space wall, is welded or otherwise secured to the ring, and affords physical support thereat for the ring and electrical connection to the exterior of the magnetron. Said lead-in rod is introduced through a hollow housing 21 sealed to the magnetron body and internally sealed with appropriate insulation as usual with lead-in rods of this character. At parts of the rings at intervals from said lead-in rods, are provided insulated struts 22 from the anode body for holding said ring rigidly in place.

A tuning electrode 23, shown in the form of a filament, extends longitudinally of at least one slot 15, and in the present showing such an electrode is provided in each said slot. Each said tuning electrode has ends thereof protruding into the end spaces 13, and those ends are secured, as by spot welding, to radially disposed spring tensioning arms 24, one at each end of each electrode, and the outer ends of said arms are secured, as by spot welding, to the respective rings 19. The invention contemplates optional choice of tuning electrode construction, material and operation. For instance, said tuning electrode may be a hot cathode, emissive of electrons due to heat generated by an electric current traversing the said cathode by virtue of connection through the arms, rings and lead-in rods. Control of the current thus applied to said tuning electrodes will vary, as desired, the electron emission from said tuning electrodes. If so desired, in addition to a heating current for said tuning electrodes, a modulation voltage may be applied from the exterior to one ring and to the anode, in which event variation in the modulation voltage effective between the tuning electrode and the anode may be utilized as the tuning means with or without altering the current applied for heating the tuning electrode. Again, if preferred, said tuning electrode may be of a character which readily emits secondary electrons released by bombardment. Such bombardment may be obtained in part by electrons from the cathode 16 of the magnetron and in part by electrons returning to said tuning electrode. To render the tuning electrode effective for tuning purposes when thus excited with secondary emission, a modulation voltage is applied, as above described, between said tuning electrode and the anode, but the source of heating current for the tuning electrode would be omitted.

In operation, electrons will emerge from the tuning electrode and will be under influence of the modulated voltage supply and under influence of the magnetic field applied to the magnetron as usual. The electrons will describe an orbit due to the influences mentioned and will in general return to the tuning electrode. The presence of the electrons from the tuning electrode and within the constricted capacitative part of the magnetron cavity will alter the dielectric constant of the space and consequently the resonant frequency of the cavity will be altered. This alteration in resonant frequency will cause a tuning or frequency shift of the magnetron.

Specifically with reference to the tuning electrode functioning as a secondary emitter, start-

ing of the emission will occur due to the collision with the tuning electrode of a few of the electrons from the magnetron cathode. Secondary electrons thereby become emitted and in normal cycle return to the electrode, thereby causing other electrons to emit, thereby releasing more electrons, thereby building up the emission from the secondary electrode rapidly. Conditions are therefore peculiarly suitable for the use of a secondary emission electrode, since no heater current is required and the operation requires none of the electrons from the tuning electrode to strike or lodge upon the anode body. A modulation voltage supply to deliver direct current will therefore not be required, but will only be needed to supply alternating current necessitated by the oscillator's shunt impedance. As the modulation voltage is varied, the electrons from the tuning electrode will vary their average distance from that electrode and consequently will modify the dielectric constant of the space within the cavity and more especially within the capacitative slot thereof, thereby changing the resonant frequency of the magnetron.

It is to be understood that while the drawing shows the tuning electrode in the form of a filament, it is illustrative of any desired cathode structure, such as thoriated tungsten or other materials, oxide coated wire and as a directly or indirectly heated cathode structure adaptable to the purpose from the prior art. Then again, for functioning as a source of secondary emission, the tuning electrode may be of suitable material for the purpose, such as alloys of silver-magnesium, beryllium-copper, pure beryllium or other substances or alloys used either as the entire body of the electrode or as a part or coating therefor. Furthermore, while the tuning electrode is shown and preferably is situated in the constricted or slot portion of the cavity, its essential location is more broadly defined as eccentric to the axis of the cavity and somewhat more specifically as in proximity to the constricted portion of the cavity.

I claim:

1. An electron discharge device having a cathode and anode with cavity resonators in the anode having constricted portions, tuning means longitudinally disposed in a cavity resonator in proximity to a constricted portion and projecting out of opposite ends of said cavity resonator, and means mounting said tuning means by said projecting ends with the major portion of said tuning means in said cavity resonator.
2. An electron discharge device having a cathode and an anode around the cathode, said anode having a cathode cavity and having cavity resonators opening into said cathode cavity, and electron emissive tuning means longitudinally disposed in one of said cavity resonators in proximity to the opening of a cavity resonator into the cathode cavity, said tuning means having a cross-section negligible in size compared to said cavity resonator whereby the cavity resonator is unobstructed to electrical lines of force longitudinal of said cavity resonator and tuning means.
3. An electron discharge device having a cathode and an anode around the cathode, said anode having a cathode cavity and having a substantially cylindrical cavity resonator opening laterally into said cathode cavity with a constricted opening, and a tuning electrode parallel to said cathode and eccentrically disposed with respect to said cylindrical cavity resonator.
4. An electron discharge device having a cath-

ode and an anode around the cathode, said anode having a cathode cavity and having a cavity resonator the major part whereof is substantially cylindrical, said cavity resonator opening laterally into said cathode cavity with a constricted opening, and a tuning electrode in said constricted opening.

5. An electron discharge device having a cathode and an anode with a cathode cavity and cavity resonators in the anode and with constricted openings from each cavity resonator into the cathode cavity, and capacity-varying electron emissive tuning means in each of a plurality of said constricted openings.

6. An electron discharge device having a cathode and an anode around the cathode, said anode having cavity resonators radiating from the region around the cathode, said cavity resonators having substantially cylindrical portions axially parallel to the cathode, and tuning means in one of said resonators axially eccentric thereto and substantially coextensive with the axial length of said resonator.

7. A magnetron comprising an enclosure, an anode body within the enclosure spaced from the ends thereof providing end spaces within the enclosure, said anode body having a cathode cavity and cavity resonators extending from one to the other of and opening into both said end spaces, a cathode in said cathode cavity, supporting rings in said end spaces concentric with the cathode and of greater diameter than the cathode cavity, and tuning electrodes supported from said rings and extending the length of and each within a cavity resonator.

8. A magnetron comprising an enclosure, an anode body within the enclosure spaced from the ends thereof providing end spaces within the enclosure, said anode body having a cathode cavity and cavity resonators extending from one to the other of and opening into both said end spaces, a cathode in said cathode cavity, supporting rings in said end spaces concentric with the cathode and of greater diameter than the cathode cavity, insulating mounting means for said rings interposed between said rings and the anode body, and tuning electrodes supported from said rings and extending the length of and each within a cavity resonator.

9. A magnetron comprising an enclosure, an anode body within the enclosure spaced from the ends thereof providing end spaces within the enclosure, said anode body having a cathode cavity and cavity resonators extending from one to the other of and opening into both said end spaces and extending laterally from the cathode cavity and providing a constriction next to and opening into said cathode cavity, supporting rings in said end spaces concentric with the cathode and of greater diameter than the cathode cavity, and tuning electrodes supported from said rings and extending the length of a cavity resonator and each within a constriction of a cavity resonator.

10. A magnetron comprising an enclosure, an anode body within the enclosure spaced from the ends thereof providing end spaces within the enclosure, said anode body having a cathode cavity and cavity resonators extending from one to the other of and opening into both said end spaces, a cathode in said cathode cavity, supporting rings in said end spaces substantially overlying a part of each cavity resonator, radially directed tensioning arms secured to said rings, and tuning electrodes supported from said ten-

sioning arms and extending the length of and each within a cavity resonator.

11. A magnetron comprising an enclosure, an anode body within the enclosure spaced from the ends thereof providing end spaces within the enclosure, said anode body having a cathode cavity and cavity resonators extending from one to the other of and opening into both said end spaces, a cathode in said cathode cavity, supporting rings in each of said end spaces and substantially next to the peripheries of said end spaces, tensioning arms secured to said rings and projecting radially inward thereof, and tuning electrodes supported between pairs of said arms in said resonators.

12. A magnetron comprising an enclosure, an anode body within the enclosure spaced from the ends thereof providing end spaces within the enclosure, said anode body having a cathode cavity and cavity resonators extending from one to the other of and opening into both said end spaces and extending laterally from the cathode cavity and providing a constriction next to and opening into said cathode cavity, supporting rings in each of said end spaces at a part thereof remote from the said constriction of the cavity resonator, a tensioning arm secured on said ring and projecting therefrom to a position overlying said constriction, and a tuning electrode supported from said tensioning arm and located in said constriction.

13. A tunable magnetron comprising a single anode having cavity resonators, and two cathodes insulated from each other and from said anode, said anode functioning as such for both said cathodes, each said cathode having means coupled thereto for applying a difference of potential between it and said anode and for applying to the two cathodes potentials differing from each other, whereby emission from one cathode is adapted to produce high frequency oscillations in the magnetron and emission from the other cathode is adapted to tune said oscillations over a band of frequencies inclusive of the produced high frequency oscillations.

14. A tunable magnetron comprising a single anode having cavity resonators, and two cathodes insulated from each other and from said anode, said anode functioning as such for both said cathodes, each of said cathode having means coupled thereto for applying a difference of potential between it and said anode and for applying to the two cathodes potentials differing from each other, whereby emission from one cathode is adapted to produce high frequency oscillations in the magnetron, and a source of modulation voltage connected to the said potential applying means of the other cathode for varying the said oscillations over a band of frequencies inclusive of the produced high frequency oscillations.
